M. H. MATSON, OF HORSEHEADS, NEW YORK.

Letters Patent No. 77,302, dated April 28, 1868.

IMPROVEMENT IN WATER-WHEELS.

The Schedule referred to in these Letters Patent and making part of the same.

TO ALL WHOM IT MAY CONCERN:

Be it known that I, M. H. MATSON, of Horseheads, in the county of Chemung, and State of New York, have invented certain new and useful Improvements in Water-Wheels; and I do hereby declare that the following is a full and exact description thereof, reference being had to the accompanying drawings, making part of this specification.

Figure 1 is an elevation of my improved wheel and curb.

Figure 2, a longitudinal section in plane $x x$, fig. 1.

Figure 3, an elevation of the wheel proper removed from the curb.

Figure 4, a central vertical section of the wheel and curb, the wheel being elevated above the curb for clearness of illustration.

Figure 5, a vertical section of the upper bearing suspending the wheel.

Figure 6, a plan of the under side of the bearing-block.

Figure 7, perspective view of the coupling-clamp of the spindle.

Figure 8, a diagram showing an elevation of the wicket-gates to one of the chutes of the curb.

Figure 9, plan of the same.

Figure 10, a view of the gearing for opening and closing of the gates.

Like letters of reference indicate corresponding parts in all the figures.

This invention consists in combining, with eccentric-chutes of the curb, horizontal partitions, which divide the water-space of said curb and wheel into compartments, whereby the water is brought in contact with the wheel in a way to act with more force and regularity of effect; and it consists also in the combination with the above device of a special arrangement of the gates, and devices for operating the same; and further, in the arrangement for suspending the wheel to secure its free and perfect action, and in the coupling of the spindle.

As represented in the drawings, A is the curb, and B the wheel proper. The curb surrounds the wheel, and is divided into a suitable number of eccentric-chutes, $a a$, as most clearly shown in fig. 2. The water admitted through these chutes is concentrated uniformly and brought in contact with the wheel at regular points.

Both the wheel and the curb are divided into sections or compartments, 1, 2, 3, &c., by means of horizontal divisions or partitions, $b b$, $b' b'$, the corresponding divisions of the two parts coinciding or coming exactly opposite each other, and fitting closely together, so that the water let on in any one of the sections will be brought to act directly on the corresponding part of the wheel.

The several sections of the wheel are provided with buckets, $c c$, c' ; the upper buckets having a centre discharge, (fig. 2,) and the lower tier having a centre and base discharge, as shown in figs. 3 and 4. The inner ends of the centre discharge-buckets simply come opposite, or a little past, the outer ends of the next buckets, by which means the most efficient, compact, and best discharge of the water is produced.

The division of the water-space between the curb and wheel thus into sections, insures several very important results. The most important is, that I am enabled to let on the water in any one of the sections independent of the others, and thus proportion my power to the resistance to be overcome. For instance, if the resistance is small, I can let on the water only in small section 3: if it is double, I can let on water only in section 2; or if the resistance is still greater, I can let on the volume through both 2 and 3, and so on.

In this manner I am enabled to proportion the power to the resistance, which equalizes the action of the wheel and economizes in the volume of water. In addition to this, when the full power is applied, the divisions insure the equal and uniform action over the whole wheel, by confining the water in its proper place, and not allowing it to spread and diffuse, by which much of the reaction is lost. The compact is very effective, and the water is held steadily in place, without too rapid escape.

The employment of the eccentric-chute a , in combination with the dividing of the water-space of the curb and wheel into compartments, as described, has the effect of distributing and applying the water uniformly and regularly over those portions of the wheel with which it is brought in contact, securing steadiness of motion, and preventing that vibration and jarring which occur where a simple scroll only is used.

At the entrance of each of the chutes α are wicket-gates, d d d , corresponding in number with and covering the sections 1, 2, 3, &c., as indicated in figs. 8 and 9. These gates are centrally pivoted at e e , and have lugs f f , to which are jointed arms g g , extending back, and jointed at the opposite end to hoops C C C , encircling the curb, and resting on supports h h .

Thus arranged, it will be seen that when the hoops are moved around, forward or back, (by a pinion, as in fig. 10, or otherwise,) the gates will be correspondingly opened or closed, as may be desired. And as each hoop and its series of gates are independent of the others, the water may be let on in either section desired. This independent opening and closing of each series of gates is essential to produce the working of the wheel, as before described. Simple sliding gates would only commence to let on the water at one end, and the sections would have to be opened successively from one end to the other. The separate swinging gates allow any one of the sections to be opened, irrespective of position.

The curb rests upon a suitable foundation that will hold it firmly in place. Instead, however, of resting the weight of the wheel upon a step at the bottom, as usual, I suspend it by the spindle D on a suitable bearing above. The connection of this bearing is shown most clearly in fig. 5. The spindle is provided with a screw-end, i , with a small square portion, k , below. Over the square portion rests a double convex block, l , and on top of this screws a nut or burr, m , with washers between, if desired. The block rests in a concave bearing-socket, n , of corresponding form, which is supported firmly on suitable timbers. The socket, at the outer and inner edges, may be turned up, so as to hold the oil. The diameter of the bearing may be such as to give the necessary strength. In a large-sized wheel, the bearing is preferably about a foot in diameter. At the bottom of the wheel, the end of the spindle simply rests in a suitable guide, to steady it; and a step may be arranged below, so that if the wheel lowers by wear, or otherwise, the step will catch it. The nut m enables the spindle to be tightened up at any time. The suspension of the wheel by the upper bearing gives great steadiness, and insures an easy action. The convex form of the block l allows play of the spindle from the centre without binding.

The bottom of the bearing-block l is provided with tangential grooves or passages, r r , (fig. 6,) pointing in that direction which will work the gum and dirt from the centre to the outside in the bearing-socket n . This keeps the bearing free from dirt, and also has a tendency to distribute the oil.

The ordinary globe-coupling S is used in the shaft. I employ, to retain it in place, a clamp made up of cup-shaped disks t t , encircling the coupling, but situated at some distance apart, and secured by bolts u u , connecting from one to the other in lugs v v .

The connections produced by these bolts have a degree of freedom and flexibility that insures a universal motion to the extent necessary to allow the bending and vibration of the spindle, but at the same time give sufficient stiffness for the rotary motion. Whenever desirable, from wear or otherwise, the disks can be tightened by screwing up the bolts.

This coupling-clamp is of much advantage employed in connection with the suspended bearing, since it compensates for any inclination or irregularity of the wheel, and allows the bearing-block to retain its natural position.

I do not claim a wheel proper whose bucket-space is divided into sections, as I am aware that the same is not new.

What I claim as my invention, and desire to secure by Letters Patent, is—

1. The water-space of the curb and wheel, each divided into compartments, 1, 2, 3, &c., by the partitions b b b ', when combined with the eccentric-chutes α α , the whole arranged and operating in the manner and for the purposes herein set forth.

2. The combination with the above of the series of gates d , and the arrangement of the hoop C , arms g , and lugs f , for operating the gates, in the manner and for the purposes specified.

3. The combination of the convex bearing-block l , bearing n , with upturned edges, to retain the oil, and the adjusting-nut m , the whole so operating as to suspend the wheel, and allow its vibration from an axial line, as set forth.

4. The combination of the clamping-disks t t and bolts u u with the globe-coupling S , operating in the manner and for the purpose herein set forth.

In witness whereof, I have hereunto signed my name in the presence of two subscribing witnesses.

M. H. MATSON.
